UNITED STATES PATENT OFFICE.

ALEXANDER N. IVANOFF, OF NEW YORK, N. Y.

MUSICAL INSTRUMENT.

Application filed October 23, 1925. Serial No. 64,430.

This invention relates to musical instruments, and more particularly to a chromatic scale harp which comprises a standard harp structure which is mounted in a horizontal 5 position on a table structure, and has extending across one end of said harp structure, a relatively narrow piano-like keyboard control mechanism for operating a plurality of string dampers in a selective 10 manner for controlling the sound emission of said harp. The object of the invention is to provide a combination harp and piano keyboard structure adapted to have sounded thereon, certain chords in a selective manner, 15 making it possible to play a composition consisting of chords.

A further object of the invention is to provide a table mounted harp structure with a keyboard operating mechanism thereon for dampening certain strings in an octave formation against sound emission, and a pair of foot pedals depend from the underside of the top structure of the table, and are connected to said harp and keyboard mechanism 25 for lifting all of the string dampers simultaneously or for silencing all the strings on the harp simultaneously, against sound emission.

Other objects of the invention will appear 30 in the following detail description, and in the accompanying drawings wherein:

Figure 1—is a top plan of the combination harp and keyboard mechanism therefor.

Figure 2—is a side elevational view of the 35 instrument showing the foot pedal mechanism.

Figure 3—is a longitudinal section through the keyboard mechanism on the line 3—3 of Figure 1.

Figure 4—is a cross section through the 40 keyboard mechanism on the line 4—4 of Figure 1.

Figure 5—is a section through the harp on the line 5—5 of Figure 1, showing the 45 pedal operated silencing bar.

Figure 6—is a vertical section on the line 6—6 of Figure 4, enlarged.

Referring more particularly to the drawings, the invention comprises the table 1 having a top structure 2 which is hollow and adapted to provide a sound amplifying chamber 3. The harp 4 is secured to the top surface of said top structure 2, in a horizontal position and is secured by means of the screw 50 6 in the harp frame 7. The top structure 2 comprises the top and bottom boards 5 and

5^a, which are spaced in order to define the sound chamber 3. The top board 5 terminates short of one end of the top structure, thereby causing an opening 5^b to be formed, 60 said frame covering all but the upper right hand corner of the top structure 2, there being provided in the said corner in the top surface thereof, a plurality of sound apertures 8 and so spaced as to simulate a design. At the extreme left end 9 of the harp structure 4, extending across the bridge head 9' thereof, is the piano key mechanism generally designated as 10, said key mechanism comprising a rectangular frame 11 which is 70 made up of the two side members 12 and the two end members 13 which are secured across the ends of the relatively long side members 12. Running parallel with and spaced between the side members 12 are a plurality of 75 actuating bars 14, which are apertured at each end thereof, and adapted to be positioned on a plurality of studs 15 secured in the end frame members 13 for slidable up and down movement thereon, said studs and a 80 plurality of coil springs 16 being disposed on the lower part of said studs and under the actuating bars 14 for returning the said bars to their normal position, said bars having depending from the underside thereof, a set 85 of four equally spaced contact pins 17, each of said bars 14 being provided with four of said contact pins which are equally spaced throughout the greater length of the bars 14, and each succeeding row on the remaining bars are spaced ahead the distance of one pin from the first pin on the first bar, as indicated at A, thereby presenting a staggered formation and said pin formation 90 adapted to provide progressive contact with 95 forty-eight damper fingers, indicated at 18, said damper fingers being disposed at right angles to the bars 14, and are pivoted intermediate their ends to spring influenced hinge brackets 19, which are in turn fixedly secured to the side face 20 of the inner side member 12, each of said damper fingers 18 having the undersurface of their contact heads 21 faced with felt padding for silent 100 contact with a like number of strings disposed on said harp.

Adjacent to one end of the key mechanism and projecting upwardly from the side frame members 12, are two upstanding ears 22 adapted to hold rigidly a key-retaining 110 cross bar 23. Said bar adapted for effecting a bearing in the V-grooves 24, which are

provided one on the upper face of each key 25 adjacent the rear end thereof, and provides the pivotal point for the downward and upward movement of each key. The 5 underside of the offset heads 26 of the keys 25 present an arcuate surface 27 for contact on the key supporting cross member 28 which extends across the undersides of the side frame members 12. Said cross member 10 28 having a plurality of upstanding pins 29 secured therein for passage through the clearance apertures 30, provided in the offset heads 26 of the keys 25. Said pins 29 adapted to retain the keys 25 in alignment with the bars 14, and to limit the downward movement of said keys.

20 Adjacent to the front or operating end of the white keys 25, on the underside thereof, are a plurality of apertures, 31, one in each key and said apertures adapted to slidably receive a like number of relatively short upstanding alignment studs 32, said studs being rigidly secured in the upper or padded face of the blocks 33 which are secured on the top surface of the actuating bars 14, and parallel therewith. The black keys 34 which are disposed between the white keys 25 in the usual order, are similarly constructed, and positioned centrally over the respective actuating bars for said black keys 34, and the pivoted ends 35 of said keys 34 also have a vertical aperture 36 through the ends 37 for passage therethrough of similar alignment pins 38, with the exception that they are placed to the right side of the retaining cross bar 23, as indicated at B.

25 The alignment pins 29 for the white keys 25, are placed to the left of said cross bar 23, as indicated at C. This is necessary for the reason that the black keys 34 are shorter in length than the white keys 25, and consequently, have a shorter leverage. The first one of the actuating bars 14 which is indicated by the numeral 39, has no contact posts 40 or key provided therefor, but has instead, an auxiliary bar 40, parallel therewith, and secured adjacent to the underside of the first bar 39, for simultaneous contact with all of the damper fingers 18. Said bar 39 being 45 connected by the pivoted rods 41 which terminate at the end of one of the pedals 42, said pedal adapted to raise all of the damper fingers 18 simultaneously. The remaining pedal 43 secured to the support 44 therefor, actuates the silencer bar 45, which is 50 connected to said pedal by means of a pivoted rod 46, said silencer bar being faced with felt, and adapted to silence all of the harp strings 47, simultaneously when pressure is applied to said pedal. The entire 55 key mechanism and the carrying frame therefor, is of such proportion, as to fit snugly on the harp frame and is held secure by a pair of screw points, and hooks 48, and a 60 suitable ornamental cover 49 is provided to

cover the complete mechanism with the exception of the aperture in its top face to expose the operating keys.

From the foregoing, it will be apparent that when a certain number of the keys are 70 depressed with the left hand, a like number of the damper fingers 18 will be raised out of contact with a like number of harp strings, which will then be open to emit sound when a suitable pick held in the fingers of the 75 right-hand, is run across all the strings of the harp. As all of the keys are each adapted to raise the four spaced intervals of the damper fingers 18, it will be readily seen by those learned in the art, that any chord or 80 combination thereof, may be sounded upon the instrument.

It is, of course, to be understood, that the invention may be constructed in various other manners, and the parts associated in 85 different relations, and therefore, I do not desire to be limited in any manner, except as set forth in the claims hereunto appended.

What I claim is:

1. The combination with a chromatic 90 scale harp, of a supporting stand therefor, said supporting stand including an amplifying sound chamber formed therein, a keyboard operated control mechanism disposed on the harp frame and over the strings of 95 said harp, pedal means for silencing all of the harp strings simultaneously, a plurality of damper fingers provided for said harp strings and actuated by the keys on said keyboard for raising and lowering a predetermined number of said damper fingers, and pedal means for raising all of said 100 damper fingers simultaneously.

2. The combination with a chromatic scale harp, of a supporting stand therefor, 105 said supporting stand including an amplifying sound chamber formed therein, a sound control mechanism disposed on the harp frame and over the strings thereof, a control keyboard embodied in said mechanism, 110 a plurality of damper fingers controlled by said keyboard, each key comprising said keyboard, adapted for raising and lowering a predetermined number of said damper 115 fingers, pedal means for raising all of said damper fingers simultaneously, and a single damper bar for silencing all of the harp strings simultaneously.

3. The combination with a chromatic scale harp, of a supporting stand therefor, 120 said stand including an amplifying chamber formed therein, a keyboard control, a damper mechanism disposed on the harp frame, said mechanism comprising a plurality of actuated bars, a plurality of damper fingers for co-operative action with a series of piano keys comprising said keyboard control in a selective manner, a pair 125 of foot pedals disposed downwardly from the underside of said stand, means for con- 130

necting one of said pedals with one of the actuating bars for simultaneously raising and lowering all of the damper fingers, and the second pedal adapted for silencing 5 simultaneously all of the harp strings.

4. The combination with a chromatic scale harp, of a supporting stand therefor, said stand including an amplifying sound chamber formed therein, a keyboard operated damper mechanism disposed in a horizontal position on the harp frame and over the strings of said harp, said mechanism comprising a frame, a plurality of actuating bars movably secured in said frame and 15 parallel with the sides of said frame having the greatest length, a plurality of piano keys pivoted and disposed in central alignment over said actuating bars for effecting contact with said bars, a plurality of damper 20 fingers disposed at right angles to said actuating bars, and pivoted adjacent to the contact ends of said damper fingers to the inner side member of said frame, a single silencing bar, pedal means for actuating 25 said bar, and pedal means for actuating all of the damper fingers simultaneously.

5. The combination with a chromatic scale harp, of a supporting stand therefor, said stand including an amplifying sound chamber formed therein, a keyboard operated damper mechanism disposed in a horizontal position on the harp frame and over the strings of said harp, said mechanism comprising a frame, a plurality of actuating 30 bars movably secured in said frame and parallel with the sides of said frame having the greatest length, a plurality of piano keys pivoted and disposed in central alignment over said actuating bars for effecting contact with said bars, a plurality of damper 35 fingers disposed at right angles to said actuating bars and pivoted adjacent to the contact ends of said damper fingers to the inner side member of said frame, a single silencing bar, pedal means for actuating all of the damper fingers simultaneously, a cover for complete keyboard control mechanism, said cover apertured to expose the keys only, and means for securing said cover and mechanism.

6. In a musical instrument, a stand comprising a top structure and an under supporting structure, said top structure having upper and lower vibrating boards spaced 55 to defining a sound amplifying chamber therebetween, the upper board terminating short of one end of the top structure and thereby causing an opening to be formed, a chromatic scale harp secured to the top 60 board with its strings spaced from the board, a sound control mechanism on one end of the top structure and over the strings of the harp and provided with a control keyboard for actuating elements of the sound 65 control mechanism for raising or silencing the tone caused by the vibration of the strings.

7. In a musical instrument, the combination with a top structure and an under supporting structure therefor, said top structure having top and bottom boards spaced to define a sound chamber, the top board terminating short of one end of the top structure causing an opening to be formed, 70 of a chromatic scale harp secured on the top board with its strings spaced from said top board, a sound control mechanism embodying a control keyboard at one end of the top structure and over the strings of the 75 harp, said sound control mechanism having a plurality of damper fingers, with means for actuating them toward and from the strings for silencing and raising the tone emanating from the strings.

In testimony whereof I affix my signature.

ALEXANDER N. IVANOFF.
